UNITED STATES PATENT OFFICE.

HANS J. ANDERSON, OF LAKEMILLS, WISCONSIN.

END-GATE FASTENER.

1,227,231.

Specification of Letters Patent. Patented May 22, 1917.

Application filed May 8, 1916. Serial No. 96,226.

To all whom it may concern:

Be it known that I, HANS J. ANDERSON, a citizen of the United States, residing at Lakemills, in the county of Jefferson and 5 State of Wisconsin, have invented certain new and useful Improvements in End-Gate Fasteners; and I do declare the following to be a full, clear, and exact description of the invention, such as will enable others 10 skilled in the art to which it appertains to make and use the same.

This invention relates generally to end gates for wagons but more particularly to fasteners for such end gates.

15 The primary object of the invention is to provide a means for the end gates of wagons, by which the same may be easily and quickly attached to or detached from the wagon body.

20 Another object of the invention is to improve upon the general construction of devices of this character by the provision of a device which will be simple, strong, durable and comparatively inexpensive in construction, efficient and reliable in operation, 25 and well adapted to the purpose for which it is designed.

With these and other objects in view, the 30 invention consists of certain novel features of construction, and the combination and arrangement of parts as will be hereinafter fully described and claimed.

In the accompanying drawings, in which 35 similar reference characters designate like parts throughout the several views,

Figure 1 is a front elevation of the rear end of a wagon body and end gate, showing a fastening device constructed in accordance with this invention applied thereto;

40 Fig. 2 is a side elevation of the inner face of the rear end of one of the sides of the wagon body with the end gate removed;

Fig. 3 is a similar view of the outer face of the rear end of the other side of the 45 wagon body with the end gate removed;

Fig. 4 is a similar view with the end gate in place;

Fig. 5 is a horizontal sectional view taken 50 on the plane of the line 5—5 of Fig. 1; and

Fig. 6 is an enlarged sectional view through one of the clamping nuts, showing particularly the swiveled connection between the same and its threaded shank.

In the embodiment illustrated, the reference character 1 designates a wagon body 55 having upright sides 2 and 3, and a hori-

zontal floor 4. Secured to the inner face of the side 2 at the rear end thereof in any suitable manner is an upright rectangular plate 5, the rear end of which is rolled inwardly and forwardly upon itself as at 6, and provided with a pair of vertically extending rectangular notches 7. Registering with the notches 7 in the plate 5 are recesses 8, the latter being arranged in the 60 inner face of the side 2 of the wagon body. 65

The rear end of the side 3 of the wagon body is provided with a pair of vertically spaced horizontally extending notches or key hole slots 9, which register with similarly arranged and shaped notches 10 in the rear edge of an upright rectangular plate 11, the latter being secured in any suitable manner to the outer face of the 70 rear end of said side 3. Extending down-

wardly through the usual apertured ears 12 of the floor 4 of the wagon body is the threaded shank portion 13 of the plate 11, said shank portion 13 being provided at its 75 lower free end with a clamping or locking

nut 14. Struck outwardly from the horizontal edges of the notches 10 of the plate 11 are flanges 15, the latter having their forward edges cut off short of the forward ends of said notches, while extending out-

wardly from the plate 11 adjacent the forward ends of the notches 10 are lugs or projections 16, the purpose of these parts being hereinafter described. 85

The reference numeral 17 designates the 90 end gate of the wagon body, which is provided at its opposite ends with pairs of vertically spaced horizontal straps 18 and 19. The inner ends of the straps 18 and 19 are connected by upright straps 20, which 95 are in turn connected midway of said connections by a horizontal strap 21, the latter being secured in any suitable manner to the rear side of the end gate 17.

The outer or free ends of the straps 18 are 100 curved rearwardly and slightly inwardly as at 22 to form suitable hooks which extend through the aforesaid openings 7 of the plate 5, and which are received in the recesses 8 in the side 2 of the wagon body. As 105 will be readily understood, this forms a detachable and pivotal connection for this end of the end gate.

The outer or free ends of the horizontal straps 19 are so shaped to form shanks 23, 110 the latter extending longitudinally from this end of the end gate 17 and disposed in

the registering notches 9 and 10. It is to be understood that when the gate is being removed these shanks 23 slide horizontally in the notches. Disposed on the threaded or free end of the shanks 23 are suitable ratchet clamping nuts 24, the latter being provided at their outer ends with suitable means whereby they may be readily engaged for turning, here shown in the form 10 of laterally extending handles 25, while their inner ends are serrated as shown, for engagement with the aforesaid lugs or projections 16 carried by the plate 11 to prevent accidental rotation of said nuts. When 15 the shanks 23 are positioned against the forward ends of the notches 9 and 10, and the nuts 24 are tightened so that their inner ends are in contact with the outer face of the plate 11 and locked against rotation in 20 the manner just described; said nuts are disposed forwardly of the forward ends of the flanges 15, which prevents the shanks 23 from becoming laterally displaced with respect to the registering notches, as will be 25 readily understood.

From the foregoing description, taken in connection with the accompanying drawings, the construction and operation of the device will be readily understood without a 30 more extended explanation, and it may also be seen that the objects of the invention have been effectively carried out, as a comparatively cheap and simple, but very effective and useful device for fastening the end 35 gates of wagons to the wagon body, has been provided.

It is to be understood, however, that the accompanying drawings simply illustrate the preferred form of the invention, and as 40 various changes in form, proportion, and the minor details of construction may be resorted to without departing from the spirit of this invention, I do not wish to be limited to this construction other than that 45 set forth in the appended claims.

I claim:—

1. The combination with a wagon body having upright sides, a metal plate secured

to the inner face at the rear end of one side with its rear edge rolled and provided with 50 vertically spaced apertures adjacent said rolled portion, said side having recesses arranged opposite the apertures in said plate, a plate secured to the outer face of the other side of said body at its rear end, said plate 55 and end having rearwardly opening registering keyhole slots, laterally extending stops at the outer ends of the slots of said plate, projections on said plate adjacent said slots and spaced inwardly from said stops; 60 of an end gate having vertically spaced laterally extending out-turned hooks at one end for engagement with the apertured plate, and threaded shanks extending longitudinally from its other end for engagement 65 with the slotted plate, and nuts on said shanks having teeth for engaging the projections on said slotted plate.

2. An end gate having transversely arranged straps on its outer face spaced from 70 the ends thereof, a longitudinally extending strap connecting said transverse straps midway the width of said gate, spaced parallel straps extending longitudinally from each of said transverse straps toward the respective ends of said gate, the longitudinal straps at one end of said gate having out-turned hooks at their outer ends, the longitudinal straps at the other end of the gate having threaded longitudinal extensions at 80 their outer ends projecting beyond said gate end; in combination with a wagon body having openings in the rear end of one of its sides to receive the hooks carried by one end of said end gate, the other side of said 85 body having notches to receive the threaded extensions at the other end of said gate, and nuts on said extensions for locking said gate to said body.

In testimony whereof I have hereunto set 90 my hand in presence of two subscribing witnesses.

HANS J. ANDERSON.
